UNITED STATES PATENT OFFICE.

JASON PAIGE, OF EVANSTON, ILLINOIS.

TRACK SWITCH.

1,423,965.

Specification of Letters Patent. Patented July 25, 1922.

Application filed December 24, 1921. Serial No. 524,572.

To all whom it may concern:

Be it known that I, JASON PAIGE, a citizen of the United States, residing at Evanston, in the county of Cook and State of Illinois, have invented certain new and useful Improvements in Track Switches, of which the following is a specification.

My invention relates to track switches and more specifically to an improved track switch 10 having heating means for preventing the formation in cold weather of ice and snow about the movable switch points.

An object of my invention is to provide such a switch having heating means incorporated in an associated part of the switch structure and so constructed as to be protected from damage due to the severe shocks incident to the ordinary use of the switch.

Another object is to provide a switch having 20 electrically heated slide plates supporting the switch points and adapted to prevent the formation of ice about the portions of the switch points supported on the plates and also about the portions between the ties.

25 In winter weather a small amount of snow or ice about the points of a track switch may entirely prevent the operation of the switch at the proper time either by filling in between the points and the rails or by freezing the movable parts solidly to the supporting structure. In consequence, track switches of ordinary construction frequently must be cleaned of snow and ice during freezing weather and following snow storms.

30 The thawing of such ice accumulations by burning oil about the switch parts, as has been customary, is expensive and is liable to damage the switch structure so that possible derailment of passing trains may result.

35 My construction of an electrically heated slide plate, when used in a track switch, efficiently prevents the formation of ice about the movable switch points supported by the 40 slide plate. I have found in connection with their use in changing weather conditions that water accumulating in the spaces between the ties and removed from the slide plates of conventional shape may freeze and 45 obstruct the operation of the switch points.

50 To prevent that occurrence, I have constructed an electrically heated slide plate having a lateral wing extending between the ties so that in the lowest temperature the 55 entire length of the switch points will be free of ice and operable at all times.

In the accompanying drawings I have illustrated a preferred embodiment of my invention, but it is to be understood that in the interpretation of the appended claims 60 they are not to be limited to the precise construction or arrangement set forth, except as may be necessitated by the state of the prior art.

Referring to the accompanying drawings, 65 Figure 1 is a fragmentary plan view of a railroad switch indicating an application of my invention thereto. Fig. 2 is an enlarged view of one of the slide plates formed with a lateral wing. Fig. 3 is a perspective view 70 of the slide plate showing the depressed section of the wing portion. Fig. 4 is a detail section showing the electrical conductor and heating element embedded in the structure of the slide plate. 75

For purposes of illustration I have shown in Fig. 1 one side of an ordinary track switch comprising a fixed rail 10 and a movable rail comprising a switch point 11, both laid upon and supported by suitable ties 12. 80 Slide plates 13, attached to the ties beneath the rails by suitable spikes or bolts 14, provide bearing surfaces for the movable switch point 11.

85 Each of the slide plates 13 are provided with lateral wings 15 extending longitudinally of the rails and bridging the space between the supporting ties. To assure non-interference with the movement of the switch point, the section of the wing 15 extending 90 between the ties is depressed a substantial space from the under side of the movable rail, as illustrated at 16 in Fig. 3.

95 The electrical heating means provided in each of the slide plates 13 comprises a resistance element 17 embedded directly in the structure of the slide plates and being arranged in loop formation through the body portion and the wing portion of the plate. The terminals 18 extend through one side of 100 the plate for connection in an electric circuit. The resistance element 17 is surrounded by a sleeve of insulating material 19 which in turn is enclosed in a metallic sheath 20 preferably made of some ductile 105 alloy adapted to permit the drawing of the assembled heating element to the desired cross-section suitable for installation in the plates.

110 In manufacturing the slide plates the heating element 17, being arranged in looped formation as illustrated in Fig. 2, is laid in

a mold and the slide plate then cast by filling the mold with molten metal which in solidifying forms a practically integral structure with the outer metallic sheath 20 of the heating element. It will be seen that a slide plate formed in this manner effectively and permanently protects the heating element, and that no shocks to the plate, short of that sufficient to fracture the plate, is liable to damage the heating means employed.

Suitable lead wires 21 may conduct electrical energy to the heating elements by conventionally arranged connections from any desired source of power, and obviously the supply may be controlled from any convenient control station.

Preferably a layer of asbestos 22 or the like is placed between each of the slide plates 20 and the tie upon which it is secured. This prevents excessive absorption of heat by the ties when they are constructed of metal or cement, and protects wooden ties from burning. Suitable drainage means for disposing of melted snow or ice should be provided in the construction of the sub-structure of the track in proximity to the heating units, and preferably should comprise tile drains embedded in the road bed and adapted to drain away the melted ice from between the ties.

It will now be apparent that I have provided an improved electrically heated slide plate which will efficiently prevent the formation of ice about the moving switch points supported on the plates, and which are especially adapted to prevent such for-

mation of ice about those sections of the movable switch points extending between the slide plates.

I claim as my invention:

1. A track switch supported on spaced ties and having, in combination, a fixed rail, a movable rail forming a switch point, slide plates on the ties providing bearing surfaces for said rails, said plates being provided with laterally extending wings underlying the portions of said rails between the spaced ties, and electrical means for heating said slide plates and lateral wings.

2. In a track switch having a fixed rail and a movable rail, a plurality of slide plates forming spaced bearings for said rails and each comprising a body portion extending transversely thereof, a wing portion extending longitudinally of said rails toward an adjacent spaced slide plate, and electric means embedded in said slide plates for supplying heat thereto.

3. A slide plate for track switches comprising a body portion adapted to form a rail bearing, a lateral wing portion, and an electrical resistance element embedded therein and adapted to heat said slide plate.

4. A slide plate for track switches comprising a body portion adapted to form a rail bearing, an integral wing portion having a depressed end section, and an electrical resistance element embedded therein and adapted to heat said slide plate.

In testimony whereof, I have hereunto set my hand.

JASON PAIGE.
